FIGURE 1 is a perspective view of a hearing aid showing my new design.

FIGURE 2 is a top plan view thereof; the undisclosed bottom side is a mirror image of the top.

FIGURE 3 is a left side elevational view thereof.

FIGURE 4 is a front elevational view thereof.

FIGURE 5 is a right side elevational view thereof.

FIGURE 6 is a rear elevational view thereof.

FIGURE 7 is a perspective view of a second modified embodiment of the hearing aid shown in FIGURE 1.

FIGURE 8 is a top plan view thereof; the undisclosed bottom side is a mirror image of the top.

FIGURE 9 is a left side elevational view of the device shown in FIGURE 7.

FIGURE 10 is a front elevational view of the device shown in FIGURE 7.

FIGURE 11 is a right side elevational view of the device shown in FIGURE 7.

FIGURE 12 is a rear elevational view of the device shown in FIGURE 7.

FIGURE 13 is a perspective view of a third modified embodiment of the hearing aid shown in FIGURE 1.

FIGURE 14 is a top plan view thereof; the undisclosed bottom side is a mirror image of the top.

FIGURE 15 is a left side elevational view of the device shown in FIGURE 13.

FIGURE 16 is a front elevational view of the device shown in FIGURE 13.

FIGURE 17 is a right side elevational view of the device shown in FIGURE 13.

FIGURE 18 is a rear elevational view of the device shown in FIGURE 13.

FIGURE 19 is a fourth modified embodiment of the hearing aid shown in FIGURE 1;

FIGURE 20 is a top plan view thereof; the undisclosed bottom side is a mere image of the top shown.

FIGURE 21 is a left side elevational view of the device showing FIGURE 19.

FIGURE 22 is a front elevational view of the device shown in FIGURE 19.

FIGURE 23 is a right side elevational view of the device shown in FIGURE 19.

FIGURE 24 is a rear elevational view of the device shown in FIGURE 19.

FIGURE 25 is a fifth modified embodiment of the hearing aid shown in FIGURE 1.

FIGURE 26 is a top plan view thereof; the undisclosed bottom side is a mirror image of the top shown.

FIGURE 27 is a left side elevational view of the device shown in FIGURE 25.

FIGURE 28 is a front plan view of the device shown in FIGURE 25.

FIGURE 29 is a right side elevational view of the device shown in FIGURE 25.

FIGURE 30 is a rear elevational view of the device shown in FIGURE 25.

FIGURE 31 is a perspective view of a sixth modified embodiment of the hearing aid shown in FIGURE 1.

FIGURE 32 is a top plan view of the device shown in FIGURE 31.

FIGURE 33 is a left side elevational view of the device shown in FIGURE 31.

FIGURE 34 is a front elevational view of the device shown in FIGURE 31.

FIGURE 35 is a right side elevational view of the device shown in FIGURE 31.

FIGURE 36 is a rear elevational view of the device shown in FIGURE 31.

FIGURE 37 is a bottom plan view of the device shown in FIGURE 31.

FIGURE 38 is a perspective view of a seventh modified embodiment of the hearing aid shown in FIGURE 1.

FIGURE 39 is a top plan view of the device shown in FIGURE 38.

FIGURE 40 is a left side elevational view of the device shown in FIGURE 38.

FIGURE 41 is a front elevational view of the device shown in FIGURE 38.

FIGURE 42 is a right side elevational view of the device shown in FIGURE 38.

FIGURE 43 is a rear elevational view of the device shown in FIGURE 38.

FIGURE 44 is a bottom plan view of the device shown in FIGURE 37.

FIGURE 45 is a perspective view of an eighth modified embodiment of the hearing aid shown in FIGURE 1.

FIGURE 46 is a top plan view of the device shown in FIGURE 45.

FIGURE 47 is a left side elevational view of the device shown in FIGURE 43.

FIGURE 48 is a front elevational view of the device shown in FIGURE 45.

FIGURE 49 is a right side elevational view of the device shown in FIGURE 45.

FIGURE 50 is a rear elevational view of the device shown in FIGURE 45.

FIGURE 51 is a bottom plan view of the device shown in FIGURE 45.

FIGURE 52 is a perspective view of a ninth modified embodiment of the hearing aid shown in FIGURE 1.

FIGURE 53 is a top plan view thereof.

FIGURE 54 is a left side elevational view thereof.

FIGURE 55 is a front elevational view thereof.

FIGURE 56 is a right side elevational view thereof.

FIGURE 57 is a rear elevational view thereof.

FIGURE 58 is a bottom plan view thereof.

I claim:

The ornamental design for a hearing aid, substantially as shown and described.
